[57] CLAIM

The ornamental design for a carrying handle, as shown and described.

DESCRIPTION

FIG. 1 is a perspective view of a portion of a carrying handle showing our new design;

FIG. 2 is a front elevational view thereof;

FIG. 3 is a rear elevational view thereof;

FIG. 4 is a top plan view thereof;

FIG. 5 is a bottom view thereof;

FIG. 6 is a left side elevational view thereof, with the right side elevational view thereof being substantially similar;

FIG. 7 is a top plan view of another embodiment of a portion of a carrying handle in accordance with the present invention;

FIG. 8 is a top plan view of yet another embodiment of a portion of a carrying handle in accordance with the present invention;

FIG. 9 is a top plan view of still another embodiment of a portion of a carrying handle in accordance with the present invention;

FIG. 10 is a top plan view of yet another embodiment of a portion of a carrying handle in accordance with the present invention;

FIG. 11 is a front elevational view thereof, with the rear elevational view thereof being substantially similar;

FIG. 12 is a left side elevational view thereof, with the right side elevational view thereof being substantially similar; and,

FIG. 13 is a bottom view thereof.
